UNITED STATES PATENT OFFICE.

OLAF W. PETERSEN, OF BUFFALO, NEW YORK, ASSIGNOR TO PETERSEN STOKER COMPANY, OF BUFFALO, NEW YORK.

GRATE.

1,424,937.

Specification of Letters Patent. Patented Aug. 8, 1922.

Application filed August 1, 1919. Serial No. 314,599.

To all whom it may concern:

Be it known that I, OLAF W. PETERSEN, a subject of the King of Denmark, residing at Buffalo, in the county of Erie and State 5 of New York, have invented a new and useful Improvement in Grates, of which the following is a specification.

This invention relates to grates of the kind by which the fuel, during the combustion thereof, can be advanced along the 10 grate.

The objects of the invention are to produce a grate of this kind comprising grate bars having a plurality of surfaces which 15 may be successively exposed to the heat of the fire and when in their normal positions form a substantially flat upper face of the grate, the grate bars being adapted to be actuated for advancing the fuel; also to 20 provide a grate of this kind which keeps itself clean and free from clinkers; also to provide a grate of this kind which automatically dumps the ashes or clinkers and in which the ash is not mixed with the 25 green fuel; also to provide a grate of this kind which is simple in construction, reliable in operation and in which defective parts can easily be replaced without necessitating the dismantling of the entire grate 30 or its removal from the furnace; also to provide a stoking grate which is of compact construction so that it can be used in a Scotch or marine type of boiler; also to improve the construction of grates of this 35 kind in other respects hereinafter specified.

In the accompanying drawings:

Fig. 1 is a sectional plan view of a boiler furnace having a grate embodying the invention installed therein.

Fig. 2 is a transverse sectional elevation of the grate, on an enlarged scale, on line 2—2, Fig. 1.

Fig. 3 is a perspective view of a bearing cap holding a grate bar in place.

Fig. 4 is a perspective view of the lower portion of a bearing for a grate bar.

Fig. 5 is a perspective view of a locking device for holding the cap on the bearing.

Fig. 6 is a longitudinal sectional elevation of the boiler on line 6—6, Fig. 1.

Fig. 7 is a fragmentary sectional elevation thereof.

Fig. 8 is a longitudinal sectional elevation thereof on line 8—8, Fig. 1, with the 55 movable parts in a different position.

Fig. 9 is a fragmentary longitudinal sectional elevation of a grate of modified construction.

A represents a boiler furnace in which a grate embodying the invention is installed, 60 the furnace shown being of the corrugated type commonly used in Scotch or marine boilers, but it will be understood that the grate is not limited to use in connection with furnaces or boilers of the kind described but may be used in any kind of 65 heating device.

The grate includes a plurality of supporting bars or members B B', two being shown in the construction illustrated, which are 70 arranged at opposite sides of the grate and on which the grate bars are rotatably supported. Each of the grate bars consists of a central supporting rod or shaft C which may be of any desired construction and on 75 which a plurality of fire supporting plates D are arranged. These plates, in the construction shown, are provided with hub portions d adapted to engage with the rod or shaft C so as to hold the plates against 80 turning relatively to the rod. The plates D which, in the construction shown, are substantially square with the corners slightly rounded off, may be of other polygonal shape which enables the plates when 85 in their normal position to form a substantially flat grate surface, and which causes the plates, when turned to project into the fire, to advance the fire in a direction away from the supply of fresh fuel. In order 90 to accomplish these results the plates could be, for example, quadrangular in form, as shown in Figs. 1 to 8, or triangular, as shown in Fig. 9. The hubs d of the plates are provided with holes through which the shaft or 95 rod C of a grate bar may extend, the holes in the construction shown being square, and the intermediate portions of the shafts or rods C are preferably formed by two intersecting webs, as shown at c, the outer edges 100 of the webs engaging in the corners of the square holes so as to hold the plates against turning relatively to the shaft C. The ends c' of the shaft C are preferably round in cross-section and are journaled in the supporting bars B B'. The plates D of adjacent grate bars are so arranged that the plates of each grate bar extend between the plates of the adjacent bars. Consequently 105 when all of the grate bars are turned in the 110

same direction, the corners of the fire supporting plates D pass into the spaces between adjacent plates and keep these spaces clear of ashes, clinkers or other obstructions, so that a free passage of air through the grates is assured at all times. When the plates are in their normal positions, the upper edges thereof are in substantially the same plane, thus forming a flat face upon which the fire rests. Since only the edges of the fire supporting plates are in contact with the fire, it will be seen that by turning the grate bars, different edges of the plates are subjected to the action of the fire. Hence with a grate having square fire supporting plates, four different fire supporting surfaces are provided, so that the life of the grate is greatly increased. The size of the fire supporting plates and the spaces between the plates may be varied in accordance with the fuel to be burned and, if desired, the plates or projections may be made integral or may be otherwise secured on the supporting rod or shaft C.

Means are preferably provided for turning the grate bars to advance the fuel and to remove the ash, and the grate bars are preferably so turned that they will always stop in positions in which the upper edges of the fire supporting plates are substantially in the same plane. This may be accomplished by any desired means, those shown in the drawings being constructed as follows:

Each of the grate bars is provided at one end with a toothed or ratchet wheel E which is suitably secured to the supporting rod or shaft C of the grate bar. This ratchet wheel is provided with teeth corresponding in number to the fire supporting edges of the plates D. The ratchet wheel, in the construction shown, is provided with a hub e, the outer surface of which is circular and on which an arm e' is rotatably mounted. The arm e' is provided with a dog F pivoted at f to the arm e' and provided with a tooth f' adapted to engage with the teeth of the ratchet wheel, and with a weighted portion f² which is adapted to yieldingly move the tooth of the dog into operative relation to the ratchet wheel E. A ratchet mechanism of any other kind may be employed, the construction shown being desirable since it is not affected by the heat of the furnace. Each of the arms e' of the grate bars is pivotally connected adjacent to its outer end to a connecting bar or rod G, which may be actuated by any suitable means, such, for example, as a link g pivotally connected at one end to the connecting bar G and at its other end to one end of a lever G' arranged outside of the furnace. When this lever G' is rocked it moves the connecting rod G from one extreme position to the other, thus causing the dogs F to en-

gage with a tooth of the ratchet wheel E and to turn the ratchet wheel through an arc equivalent to the arc between adjacent teeth. This causes the grate bars to be rotated from a position in which the flat edges of the fire supporting plates are in substantially the same plane to a position in which other edges of the fire supporting plates are in a similar position. While the grate bars are moving from one of these operative positions to another, the fire supporting bars assume positions such as shown in Figs. 7 and 8, in which the corners of the fire supporting plates pass into the body of the fuel and advance the same in a direction away from the front of the furnace or from the supply of fresh fuel. A certain amount of ash is also removed from the fuel when the grate bars are rotated and passes between the fire supporting plates. After actuation of the lever G', a different edge of each of the fire supporting plates is subjected to the action of the fire and the edge which was previously in the fire supporting position is given a chance to cool, the lever G' being preferably so arranged that when moved to the limits of its movement the fire supporting plates will be in such positions that their upper edges lie substantially in the same plane. Any other means for rotating the grate bars through the desired angle may be employed.

At the front end of the grate a stationary finger bar H is preferably provided having fingers projecting into the spaces between the fire supporting plates, and at the rear of the furnace a bar H' is provided which extends a slight distance beyond the last grate bar. Any clinkers which pass over the grate from the front end of the furnace to the rear and which do not pass between the fire supporting plates are discharged through the space between the last grate bar and the rear bar H'. These bars may be of any other suitable or desired construction.

The grate bars may be journaled or rotatably mounted on the supporting bars B B' in any suitable manner, and are preferably supported thereon in such a manner as to be readily removable in case repairs are required. In the construction shown, the bars B and B' are provided with bearings I for the rounded ends of the bars or rods C of the grate bars. These bearings are preferably formed integral with the side supporting members B and B'. Above the bearings I, the supporting members are preferably provided with guide portions i which, in the construction shown, are rounded or convexed, and are adapted to engage with correspondingly concaved portions i' of bearing cap members I'. Each cap member is provided with a bearing portion i² corresponding to the bearing portion I so that when the cap member is in operative posi-

tion the bearing parts I and I' form a bearing for the shaft C of a grate bar. The cap member I' will be retained in its operative position in the supporting member but, if 5 desired, a locking device may be employed for positively holding the bearing cap against upward movement. In the construction shown for this purpose, the upper flanges K of the supporting members B' B' 10 are provided with inclined faces k and each bearing cap is also provided with an upper flange portion k' provided with a correspondingly inclined edge k². When a bearing cap is in operative position, a key k³ 15 having parts k⁴ adapted to straddle the web portion of the supporting member of the grate can be inserted between the inclined faces k and k², as shown in Fig. 6, and thus hold the bearing caps in place on the supporting members in the grate. In order to 20 remove a grate bar from the grate it is only necessary to disconnect the arm e' from the connecting rod G, then to remove the locking keys k³ if the same are used, and to raise 25 the bearing caps I'. The bar can then be readily removed from the grate and in case one or more of the fire supporting plates are damaged, they can easily be removed from the central shaft C of the grate bar and can 30 be replaced by others. The upper flange K of the supporting part B' preferably extends into close proximity to the fire supporting plates D and the corresponding flange of the supporting member B extends 35 over the ratchet wheels E and the arms e, thus protecting them against injury from the fire.

The grate bar described has the advantage 40 that the fire supporting plates when in their normal positions have their upper or fire supporting edges substantially in the same plane so that no parts of the grate extend upwardly into the fire, which would cause these parts to burn off and would result in 45 rapid deterioration or burning out of the grate. Furthermore, the corners of the plates described, when the grate bars are turned, project into the fire far enough to advance the fuel even when the grate is ar- 50 ranged in a horizontal plane. This makes it possible to use this grate in Scotch or marine boilers in which stoking grates have heretofore not been used for the reason that the furnaces in these boilers are necessarily 55 quite small and an inclined grate could not be used therein. The grate takes up very little space and keeps itself clean, since the corners of the plates in passing between the plates of an adjacent grate bar clear out any 60 obstruction which may have settled between these plates, so that a good draft is ensured through the grate at all times. In firing a boiler equipped with this grate, the fuel is all placed on the front of the grate and is 65 then fed to the rear by the rotation of the

grate bars. This makes it possible to provide a substantially smokeless fire since the smoke from the green fuel at the front of the grate passes over the hot fuel in the middle and rear portions of the grate where it is 70 consumed. The action of the grate in advancing the fuel during the combustion thereof also makes the grate readily adaptable for automatic stokers. The grate, furthermore, can be easily repaired, since fire 75 supporting plates which have become injured can be readily replaced by other plates with very little expense since the parts of the grate bars which are uninjured can be used in connection with the new parts. 80

I claim as my invention:

1. A grate including a plurality of rotatably mounted grate bars, each of said grate bars having a central supporting rod, and a plurality of plates secured to said supporting rods and spaced apart, the plates of one grate bar being adapted to enter into the spaces between the plates of an adjacent grate bar, said plates having a plurality of substantially flat edges, and intermittently operating mechanism for turning said grate bars for advancing the fuel; said mechanism after each operation leaving the grate bars in positions in which the uppermost flat edges of the plates lie substantially in the same plane to form a substantially flat grate surface. 90
2. In a grate, the combination of a grate bar including a central supporting rod, a plurality of fire supporting plates arranged on said rod and rotatable therewith, a fixed bearing for said rod, a ratchet wheel secured on said rod and arranged adjacent to said bearing, means rotatably arranged on said rod adjacent to said ratchet wheel and cooperating with said ratchet wheel to turn said grate bar through a predetermined angle, said bearing including a removable cap having a flange overhanging said ratchet wheel and said means for turning said grate bars, to protect said ratchet wheel and turning means against the action of the fire and to render these parts readily accessible. 100
3. A grate including a plurality of grate bars, each having a number of transversely extending polygonal plates arranged with their flat faces in substantially upright planes and spaced apart, the edges of said plates in their normal position lying substantially in the same plane to form a substantially flat grate surface, the plates of each grate bar being adapted to enter into the spaces between plates of an adjacent grate bar for clearing said spaces of ash and the like, ratchet wheels on said grate bars having teeth corresponding in number to the number of edges of said plates, and intermittently operating means cooperating with said ratchet wheels for turning said grate bars to advance the fuel, said means leav- 110

ing said plates in positions in which the upper flat edges of the plates are substantially in the same plane.

4. A grate including a plurality of rotatably mounted grate bars, each of said grate bars having a central supporting rod, and a plurality of plates secured to said supporting rods and spaced apart, the plates of one grate bar being adapted to enter into the spaces between the plates of an adjacent grate bar, said plates having a plurality of substantially flat edges, supporting members at the sides of said grate in which the grate rods are journaled, intermittently operating mechanism arranged at the side of said grate for turning said grate bars to advance the fuel, said mechanism, after each operation thereof positioning said plates with their uppermost edges in substantially the same plane after each operation of advancing the fuel, and a flange on the upper edge of said supporting member for protecting said mechanism from the action of said fire.

25 5. A grate including a plurality of rotatable grate bars, supporting members at the

sides of said grate, each of said members having a vertical web and a substantially horizontal upper flange and having recesses in its upper portion forming bearings for 30 said grate bars, bearing caps loosely fitting into said recesses and movable vertically into and out of said recesses and having upper flanges extending substantially continuously with said flanges of said supporting members, contiguous edges of the flanges of said bearing caps and supporting members being bevelled, and inclined key members having flange portions engaging between said bevelled edge of the upper 40 flanges of said bearing caps and said supporting members for releasably securing said grate bars in place, said key members also having bifurcated portions straddling said vertical web of said supporting members.

Witness my hand, this 24th day of July, 1919.
